UNITED STATES PATENT OFFICE

2,332,606

FILING APPARATUS

Richard P. Scholfield, New York, N. Y., assignor
to Scholfield Service, Inc., New York, N. Y., a
corporation of New York

Original application April 1, 1941, Serial No.
386,326. Divided and this application August
26, 1942, Serial No. 456,252

7 Claims. (Cl. 129—16)

The present invention relates to filing apparatus of the type wherein a plurality of cards are secured upon the periphery of a rotatable filing drum, to facilitate access to a great plurality of cards by an operator. The invention includes modifications of, improvements upon and additions to filing apparatus of the types shown in the prior patent to Scholfield et al. No. 2,046,655, July 7, 1936 and in my application Serial No. 75,883, filed April 22, 1936, now Patent No. 2,231,029. This application is a division of my application Serial No. 386,326 filed April 1, 1941, since matured into Patent No. 2,316,489 dated April 13, 1943.

An object of the present invention is to provide improved card retaining rail structures, adapted to perform certain new and improved functions.

A further object of the invention is to provide improved card retaining means, whereby a plurality of cards may be removed simultaneously or en bloc from the periphery of the drum.

A further object of the invention is to provide improved card retaining rail shapes and cards having novel slots therein adapted to cooperate with the rails, to secure the cards thereon in an improved manner.

A further object of the invention is to provide a rotary filing drum wherein the cards may be placed upon the periphery of the drum and removed therefrom by movement along a line inclined with respect to the drum axis, and held on the drum by means engaging inclined slots in the cards and additional means engaging the ends of the cards, the last-mentioned means being adapted normally to prevent such combined inclined movement of the cards, but being mounted for movement to an inoperative position, to permit removal of the cards by such inclined, combined axial and radial movement.

With filing drums of the type shown in the aforementioned applications, the cards are placed upon the card retaining rails by flexing the material of the cards adjacent the keyhole-shaped slots therein, thereby effectively but temporarily widening the opening at the narrow throats of the slots and permitting them to move over the rail heads. For a great many uses, drums and cards of that type are entirely satisfactory, but, in some cases, it is desirable to remove, from a drum, a relatively great plurality of cards simultaneously, as a group. The present invention provides a number of different constructions wherein the cards may be readily removed from the drum periphery by combined radial and axial movement.

A number of preferred embodiments of the invention are shown in the accompanying drawing, but it must be understood that the invention is not limited to the specific details of construction

shown herein and described below, as many modifications will readily occur to one skilled in the art, from a consideration of the disclosure of this specification.

In the drawing:

Figure 1 is an enlarged sectional view through the rim and head of a filing drum in accordance with the present invention.

Figure 2 is a similar view of a half section of the drum, showing a modified card and engaging member and,

Figure 3 is a fragmentary sectional view of a further modification.

As shown in Figures 1 and 2, the filing drum comprises a rim 100 carried by circular shoulders formed integrally upon heads 116 and 119. The cards may be removed en bloc from the card retaining rails by movement on lines inclined with respect to the drum axis. The card retaining rails have surfaces inclined outwardly toward one end of the drum, and the cards have similarly shaped openings, so that they may be removed therefrom or mounted thereon by combined axial and radial movement.

In Figure 1 the rim 100 is provided with a pair of outwardly projecting circumferentially continuous ribs or rails 101, each of which is inclined toward the end 102 of the drum. The side faces 103, 104 of the ribs are on parallel lines, in section. Actually these faces are on concentric frusto-conical surfaces.

The cards have openings 105 adjacent their inner ends, the margins of the openings being substantially parallel with the adjacent margins of the ribs, except that the margin 106 is cut back somewhat to permit the cards to be swung rearwardly or forwardly for access to the material thereon. When in the inclined position, the arcuate edge 107 of each opening rests upon and makes line contact with the outer end of the associated rib.

At one end, the drum head may be provided with a circumferentially continuous outwardly projecting flange 108, while at the other end, the head 102 is cut away at one or more sections, where a radially movable end member or gate 109 is mounted. This member is urged outwardly by spring means 110 into position to engage the end edges 111 of the cards, the spring being seated upon an appropriate ledge 112 associated with the drum head 102. If desired, the outer edge portion of the head 102 may be dispensed with entirely and the member 109 may be made circumferentially continuous.

When it is desired to remove a plurality of cards from the rim 100, the movable member 109 of the drum head is simply pressed radially or shifted axially inwardly, so as to be disposed out of line with the cards and out of contact with the end edges 111 thereof. Thereupon, the cards may

be withdrawn by combined axial and radial movement, on an inclined path, as indicated by the arrows in Figure 1.

The construction shown in Figure 2 differs from that just described only in that the continuous annular flange 115 is secured to the drum head 116 by springs 117, mounted on the ends of the tie-bolts 118, which secure the drum heads 116, 119 together. Thus, the card retaining flange 115 may be swung outwardly or depressed radially to the dotted line position in Figure 2, to clear the ends of the cards, at any point around the circumference of the drum, to permit cards to be inserted or withdrawn at will. This mounting is somewhat simpler than that shown in Figure 1. However, if the member 109 is in the form of a continuous ring, the cards at any position on the drum may be readily removed, or new cards added, in both constructions.

In Figure 3, the cards may be removed by swinging outwardly a hinged, arcuate gate 125 which is normally held in the operative card retaining position by a spring 126. The end wall 127 adjacent the gate is provided with an inclined surface 128, so that the cards may clear the member when the gate is swung to the open position. Any desired number of such pivoted, arcuate gates may be provided as a substitute for one or more of the sliding gates shown in Figure 1.

The operation of the apparatus of the present invention will be apparent to those skilled in the art from a consideration of the foregoing description. Cards en bloc may be applied to or removed from the rims by a combined endwise and radial movement, when the card retaining end member has been moved to an inoperative position.

Although the invention has been described with considerable particularity by reference to the specific embodiments shown in the accompanying drawing, it must be understood that it is not limited to the details described above and shown in the accompanying drawing, but covers all modifications coming within the scope of the appended claims and their equivalents.

I claim:

1. A filing drum comprising a cylindrical rim, a substantially continuous, non-headed card retaining rail associated therewith having a side face projecting outwardly in inclined relation toward one end of the rim, whereby cards having slots similar in shape to the rail may be removed therefrom by combined radial and axial movement toward that end of the rim, and outwardly projecting means adjacent said end of the rim, positioned to engage the ends of the cards and to prevent such movement thereof, at least a portion of said means being movable to permit such movement and removal of cards en bloc.

2. A filing drum comprising a cylindrical rim, a pair of parallel, substantially continuous, non-headed card retaining rails associated therewith, each having a side face projecting outwardly in inclined relation toward one end of the rim, whereby cards having pairs of slots similar in shape to the rails may be removed therefrom by combined radial and axial movement, and an outwardly projecting member adjacent said end of the rim and positioned to engage the ends of the cards and prevent such movement, at least a portion of the end member being movable to permit such movement and removal of cards en bloc.

3. A filing drum comprising a cylindrical rim,

a substantially continuous card retaining rail having parallel side faces projecting from the rim in inclined relation toward one end of the drum, whereby cards having slots therein may be removed from the rail by combined radial and axial movement toward that end of the drum, and an outwardly projecting end member positioned to engage the ends of the cards and prevent such axial movement, at least a portion of the end member being displaceable out of the path of movement of the cards, whereby a plurality of cards may be removed en bloc by such movement.

4. A filing drum comprising a substantially cylindrical rim, a substantially continuous card retaining rail associated therewith and projecting outwardly therefrom in inclined relation, whereby cards having inclined slots adjacent their lower edges may be placed on and removed from the drum by combined axial and radial movement on an inclined path, and abutment means at one end of the drum adapted to prevent such axial movement of the cards, said abutment means being movably mounted for displacement to an inoperative position, to permit removal of a plurality of cards by such movement.

5. A filing drum comprising a substantially cylindrical rim, a substantially continuous card retaining rail associated therewith and projecting outwardly therefrom in inclined relation, whereby cards having inclined slots adjacent their lower edges may be placed on and removed from the drum by combined axial and radial movement on an inclined path, abutment means at one end of the drum adapted to prevent such axial movement of the cards, said abutment means comprising a radially movable section, spring means urging the same outwardly into card-end abutting position, and means whereby the section may be forced inwardly to permit removal of cards from the drum by said combined axial and radial movement.

6. A filing drum comprising a substantially cylindrical rim, a substantially continuous card retaining rail associated therewith and projecting outwardly therefrom in inclined relation, whereby cards having inclined slots adjacent their lower edges may be placed on and removed from the drum by combined axial and radial movement on an inclined path, and abutment means at one end of the drum, adapted to prevent such axial movement of the cards, said abutment means including a hinged section, whereby the same may be swung to an inoperative position to permit the removal of cards by such combined axial and radial movement.

7. A filing drum comprising a substantially cylindrical rim, a substantially continuous card retaining rail associated therewith and projecting outwardly therefrom in inclined relation, whereby cards having inclined slots adjacent their lower edges may be placed on and removed from the drum by combined axial and radial movement on an inclined path, and abutment means at one end of the drum, adapted to prevent such axial movement of the cards, said abutment means comprising an annular flange and spring means connecting the flange to the drum, whereby the flange may be moved to an inoperative position, to permit removal of cards by combined axial and radial movement.

RICHARD P. SCHOLFIELD.
